UNITED STATES PATENT OFFICE

EVERRARD JOHN SULLIVAN, OF RACINE, WISCONSIN, ASSIGNOR TO WALKER MANUFACTURING COMPANY, OF RACINE, WISCONSIN, A CORPORATION OF WISCONSIN

TIRE PUMP

Application filed May 5, 1932. Serial No. 609,459.

This invention relates to certain new and useful improvements in a tire pump, of the small hand operated type adapted for carrying in a tool-kit for the emergency inflation of tires.

The principal object of the invention is to provide an improved means for simply and economically securing the pump cylinder within the supporting base plate.

Other objects and advantages of the invention will be more apparent from the following detailed description of one approved type of tire pump built according to the principles of this invention.

In the accompanying drawing:

Fig. 1 is a side elevation of the complete pump.

Fig. 2 is a central vertical section through the lower portion of the pump, taken substantially on the line 2—2 of Fig. 3.

Fig. 3 is a horizontal section taken substantially on the line 3—3 of Fig. 2.

The pump comprises a tubular cylinder 1 of any suitable length formed of sheet metal in a well known manner. The base plate 2 in the form here shown is stamped or pressed from sheet metal and is of an oblong or elliptical form to provide a foot-rest 3 at either side of the vertical pump cylinder 1. The edges of the base 2 are flanged downwardly at 4, and the central portion of the base is pressed downwardly to form an open socket for snugly receiving the lower end of the tube 1. This socket is enclosed between the downwardly extending side walls 5 and the substantially horizontal bottom wall 6, so that the socket opens upwardly. The lower end portion 7 of the tube 1 is adapted to fit snugly within the socket, but need not be connected therewith by screw threads or other external securing means, as is usual in such constructions.

A rather thin metal disc 8 of substantially uniform thickness is dished upwardly, that is, is convex on its upper surface and concave on its lower surface, and is of a diameter such that it will fit fairly snugly within the tube 1, but may be forced downwardly through this tube with the convexed or crowned surface of the disc 8 uppermost.

When the disc 8 reaches the lower end of the tube, additional pressure exerted by a mandrel or other means projecting downwardly through the tube will tend to flatten out the disc and expand its periphery into 55 tight engagement with the lower end 7 of the tube, thus jamming or expanding the tube into engagement with the wall 5 of the socket and tightly sealing the parts together.

One side wall of the tube 1 is bulged outwardly, as indicated at 9, adjacent the lower end of the tube, and a metallic nipple 10 is riveted within this bulged portion 9, the flexible air hose 11 being secured to the nipple by a suitable clamping means indicated at 66 12. The other end of the hose 11 is provided with a fitting 13 for engagement with the tire-valve in well known manner.

The piston rod 14 provided with a suitable handle 15 at its upper end, projects downwardly through the clamp 16 mounted in any suitable manner on the upper end of tube 1. The piston carried at the lower end of rod 14 comprises the leather cup or gasket 17, the upper metal plate or washer 18, and the lower spacing cup 19, this assembly being secured together by the downwardly projecting reduced end portion 20 of the rod 14 which projects through suitable openings in the members 17, 18 and 19 and is riveted over at 80 its lower end, as indicated at 21. A short compression spring 22 is mounted around the rod 14 above the plate 18 to engage the cap 16 at the upper end of the stroke and absorb shocks. As the piston is forced downwardly, the leather cup 17 will expand and trap the air, which is compressed and forced outwardly through the tube 11 in the usual manner. The spacing cup 19 will engage the upper surface of sealing disc 8 and limit the downward stroke of the piston so as to prevent injury to the sealing gasket 17 by engagement with the nipple 10. It will be apparent that the engagement of cup 19 with the upwardly dished surface of disc 8 at the lower end of the stroke will tend to seal the base and tube even more firmly together instead of having any tendency to break the connection between these parts. The parts are all of simple construction and easy to as-

semble and a very tight and permanent seal is provided at the lower end of the cylinder.

I claim:

1. In a tire pump, a tubular pump cylinder, a sheet metal supporting base formed with an upwardly opening socket closed at its lower end and having cylindrical side walls to snugly receive the lower end of the tube, and an upwardly dished sheet metal disc forced downwardly through the tube and expanded within the lower end of the tube by pressure applied upon the upwardly extending crown of the disc so that the peripheral edge of the disc is forced outwardly to clamp the tube within the cylindrical socket.
2. In a tire pump, a tubular pump cylinder, a sheet metal supporting base formed

with an upwardly opening socket shaped to snugly receive the lower end of the tube, an upwardly dished metal disc forced downwardly through the tube and expanded within the lower end of the tube by pressure applied upon the upwardly extending crown of the disc to secure the tube within the socket, an outlet nipple mounted in one wall of the tube adjacent the base, and a piston assembly movable vertically within the cylinder and comprising a downwardly cupped gasket and a downwardly projecting rigid member adapted to engage the upper crowned surface of the sealing disc to limit the downward stroke of the piston before the gasket engages the nipple.

EVERRARD JOHN SULLIVAN.
